UNITED STATES PATENT OFFICE.

JOHN HAWLEY TAUSSIG, OF PHILADELPHIA, PENNSYLVANIA.

VERTICAL-RETORT GAS APPARATUS.

951,856.

Specification of Letters Patent. Patented Mar. 15, 1910.

Application filed February 1, 1908, Serial No. 413,786. Renewed September 14, 1909. Serial No. 517,748.

To all whom it may concern:

Be it known that I, JOHN HAWLEY TAUS-
5 SIG, a citizen of the United States, residing
at Philadelphia, in the county of Philadel-
phia and State of Pennsylvania, have in-
vented certain new and useful Improve-
ments in Vertical-Retort Gas Apparatus, of
which the following is a specification.

The present invention relates more par-
10 ticularly to the arrangement of the mouth
pieces of the vertical retorts and their ac-
cessories and its principal objects, are to
provide an arrangement of connecting, take-
off and dip pipes by which the vertical re-
15 torts may be spaced and arranged in any
required position and by which a multi-
plicity of horizontally arranged pipes, of
which many are of necessity curved, is
avoided; to permit the hydraulic main to be
20 placed on the setting without the use of
curved take-off pipes; to effect a saving not
only in the cost of construction, but also in
operating expenses; and to provide for the
ready cleaning of the connecting and take-
25 off and dip pipes.

The invention will be first described and
finally claimed and the description will be
made in connection with the particular em-
30 bodiment of the invention chosen for illus-
tration in the accompanying drawings, in
which—

Figure 1, is a side view of the mouth
pieces of the vertical retorts showing their
connections and also a part of the setting
35 with the hydraulic main mounted thereon.
Fig. 2, is a top or plan view of a group of
retorts. Fig. 3, is a front view partly in
section of the hydraulic main, and Fig. 4,
is a transverse sectional view of the same.

40 In the drawings 1, 2, 3, are the mouth
pieces of vertical retorts arranged in a suit-
able setting A, and from which gas is led to
the hydraulic main 4, from which it is con-
ducted by a pipe 5. The hydraulic main is
45 arranged on the setting A, which in many
instances, is an advantageous location for it.
6, 7, and 8, and 9, 10 and 11, are additional
groups of mouth pieces. The number of re-
50 torts in each group is not material and the
point is that the mouth pieces of each re-
tort are connected from one to another and
then to the hydraulic main. By this ar-
rangement of connections, it is possible to
55 space and arrange the retorts in any de-
sired manner, which would naturally be in
such manner that they occupy the minimum

of space. The retort mouth pieces are
usually arranged upon substantially the
same level and the groups of mouth pieces
and their connections may be all substan-
tially alike, so that a description of the
connections of one group will be sufficient.

The arrangement of the retorts and their
mouth pieces having been selected and de-
termined so as to best meet the conditions
and requirements of the setting, the retort
mouth pieces are divided into suitable groups
and the connecting pipes 12 serve to con-
nect the mouth pieces in each group. These
pipes 12 are straight and as shown are ar-
ranged at such inclination to the axes of the
retorts that their high ends are accessible
for the reception of a cleaning tool through
the opening at the end of one of the retorts.
For example, the connecting pipe 12, be-
tween the retorts 1 and 2, can be cleaned by
a tool introduced through the open upper
end of the retort 2. There is a V-shaped
pipe, of which one arm 13, is straight and
constitutes the take-off pipe which connects
the interconnected group of retorts with the
hydraulic main and rises at an inclination
to the axes of the retorts, and of which the
other arm constitutes a dip pipe and dips
into the hydraulic main. The described
construction of this combined take-off and
dip pipe fitting permits the hydraulic main
to be placed upon the setting and it does not
involve any curved pipes.

15, is an opening at the point of the V-
shaped fitting and it is usually closed, but
it can be opened so as to insert through it a
tool which may be used for cleaning the dip
and take-off branches.

What I claim is:

1. In combination vertical retorts divided
into groups and having mouth pieces, and
straight connecting pipes communicating
with adjacent retorts of each group and ar-
ranged at an inclination thereto so as to be
accessible through a retort mouth piece, sub-
stantially as described.

2. In combination vertical retorts divided
into groups and having mouth pieces,
straight connecting pipes communicating
with adjacent retorts of each group and ar-
ranged at an inclination thereto so as to be
accessible through a retort mouth piece, a
hydraulic main, and a V-shaped pipe having
one of its arms in communication with the
water seal and the other of its arms in com-
munication with the group of retorts and

having an opening at the union of its arms through which they can be cleaned, substantially as described.

3. In combination vertical retorts having 5 mouth pieces in the same horizontal plane, connecting pipes laterally arranged in respect to the mouth pieces and interconnecting said retorts in groups, and a take-off pipe for each group of retorts, substantially 10 as described.

4. In combination a setting including vertical retorts having mouth pieces at the top

thereof, a hydraulic main mounted on the setting, connecting pipes connecting said retorts in groups, and angularly arranged 15 dip and straight take-off pipes, substantially as described.

In testimony whereof I have hereunto signed my name.

JOHN HAWLEY TAUSSIG.
